(57) **CLAIM**

What is claimed is the pot hanger assembly, as shown and described.

DESCRIPTION

FIG. 1 is a front elevational view of a pot hanger assembly showing my new design, the undisclosed rear being a mirror image;

FIG. 2 is a left side elevational view thereof;

FIG. 3 is a right side elevational view thereof;

FIG. 4 is a bottom plan view thereof;

FIG. 5 is a front elevational view of a second embodiment of a pot hanger assembly showing my new design;

FIG. 6 is a right side elevational view thereof, the undisclosed left side being a mirror image;

FIG. 7 is a bottom plan view thereof;

FIG. 8 is a rear elevational view thereof;

FIG. 9 is a front elevational view of a third embodiment of a pot hanger assembly showing my new design, the undisclosed rear being a mirror image;

FIG. 10 is a left side elevational view thereof;

FIG. 11 is a right side elevational view thereof; and,

FIG. 12 is a bottom plan view thereof.

No claim is made to the top plan view for each of the three embodiments.
